WILLIAM JACOBY, OF SIOUX FALLS, SOUTH DAKOTA, ASSIGNOR TO AUTOMATIC TOOL SUPPLY COMPANY, OF SIOUX FALLS, SOUTH DAKOTA, A CORPORATION OF SOUTH DAKOTA.

MAGAZINE TACK-HAMMER.

1,262,803.

Specification of Letters Patent. Patented Apr. 16, 1918.

Application filed February 13, 1917. Serial No. 148,883.

To all whom it may concern:

Be it known that I, WILLIAM JACOBY, a citizen of the United States, residing at Sioux Falls, in the county of Minnehaha, 5 and State of South Dakota, have invented certain new and useful Improvements in Magazine Tack-Hammers; and I do hereby declare the following to be a full, clear, and exact description of the same when taken in 10 connection with the accompanying drawings, forming part of this specification.

This invention relates to an improved magazine tack hammer, and has especial reference to the type of hammers, which embody 15 bodies in its construction a magazine receiving a supply of tacks or nails, from which the tacks are fed one at a time into position for being set by a blow of the hammer.

20 In addition to generally improving the construction and efficiency in operation of a device of this character, special objects of the invention are:—the provision of a novel device or cut-off, which, on each operation thereof, will absolutely insure the delivery 25 of one tack only into setting position; the provision of a magazine tack hammer having the magazine located in the head of the hammer, with a channel for delivering the 30 tacks into setting position leading from the magazine down the head of the hammer, whereby the centrifugal force produced by swinging the hammer and the force of the hammer blows may be utilized to shake the 35 tacks out of the magazine into the delivery channel; and the provision of a novel device for retaining a tack in setting position on the hammer head, which will permit a quick release of the tack from the hammer by a 40 movement of the hammer, after the tack has been properly set in the article to be tacked, or nailed, and before the tack has been driven home.

With the above general and special objects 45 in view, the invention consists in certain novel constructions, arrangements and combinations of parts, hereinafter described in a preferred form, and set forth in the claims at the end of the specification.

50 In the drawings:—

Figure 1 is a side elevation of a magazine tack hammer constructed in accordance with the present improvements.

55 Fig. 2 is a front end elevation of the hammer head.

Fig. 3 is a rear end elevation of the hammer head, the view being in section on the line 3—3 of Fig. 1, and illustrating in detail the improved cut-off in normal position.

Fig. 4 is a view similar to Fig. 3, but 60 showing the parts of the cut-off in position for permitting a single tack to pass around into setting position.

Fig. 5 is a detail view of the operating rod and the pivoted finger piece of the 56 cut-off.

Fig. 6 is an elevational view of the hammer with parts broken away to illustrate the interior construction of the head.

Fig. 7 is a section on the line 7—7 of Fig. 70 6, looking in the direction of the arrow.

Fig. 8 is a side elevational view of the hammer head looking in the opposite direction from that of Fig. 1.

Like characters of reference in the several figures indicate the same parts.

In the illustrated embodiment of the invention, the hammer head 1, which may be of any desired form or shape, consists of the two sections or plates 2 and 3, suitably 80 riveted together and forming a hollow head, as shown. The plates 2 and 3 may conveniently be formed of drop forgings. When secured together these half-sections 2, 3, are designed to support the usual handle 4 and for this purpose they are provided with rearwardly extending arms 5, between which the inner end of the handle 4 is inserted and rigidly secured, in any preferred manner.

If desired the sides of that portion of the handle inserted between the arms 5 may be flattened so as to afford engagement between the inserted portion of the handle and arms 5 at all points and permit absolutely rigid 95 securing of the handle to the head. As shown, the inner end 6 of the handle, when in position on the head, terminates short of the inner end face of the head, for a purpose which will presently appear.

The half sections 2 and 3 are provided at their upper ends with thickened portions or shoulders 7 which are brought into engagement with each other, when the half sections of the head are secured together. The 105 lower ends of the half sections 2, 3, are formed with enlargements 8 provided with striking faces 9, the latter mutually constituting the striking face of the hammer. Each half section 2, 3, is provided with a 110

rear turned flange 10, having an upper portion 11 connected by a forwardly inclined portion 12 located in front of the extension 5, with the lower portion 13. The 5 lower portions 13 of the flanges merge into the enlargements 8 at the lower end of the hammer head and the inner faces 14 of the flanges at this point connect with curved inner lateral flanges 15 cut from the inner 10 longitudinal faces of the enlargements 8. Said flanges 15 extend clear to the front face of the hammer, as shown in Fig. 2. When the two halves of the hammer head are secured together, the inner edges of the 15 flanges 10, throughout their entire extent, are spaced apart sufficiently to receive the shank of a tack, and the striking faces 9 of the enlargements 8 are similarly spaced apart. There is thus formed a channel 15^a 20 having a slot 16 wide enough to permit passage of the shanks of the tacks T which project rearwardly beyond the flanges, as shown, but not wide enough to allow the heads of the tacks to pass through, the heads 25 being retained by the flanges. It will be seen that the heads of the tacks passing down the channel 15^a are retained first by the upper, middle and lower portions of the flanges 10, and next by engagement with the 30 lateral flanges 15 of the enlargements 8. After being set by a blow of the hammer the head of a tack retained between said enlargements may pass out the front of the hammer, in the manner which will herein- 35 after appear.

The depth of the channel 15^a is determined by a metal plate 17 located within the hollow hammer head and secured to the half-sections 2 and 3 thereof, by means of rivets. 40 Said plate 17 is provided with an upper section 18 located directly behind the upper portion 11 of the flanges 10 and connected by a rearwardly projecting flange 19 with an inclined section 20 which is located in 45 front of the inclined portion 12 of the flanges 10. The inclined section 20 of the plate merges into the lower section 21, which is positioned just in front of the lower portion 13 of said flanges 10, the lower end 22 of 50 said plate terminating some distance above the flanges of the enlargements 8 to permit free passage of the tacks. Upper section 18 of plate 17 is spaced a greater distance from the flanges 10 than the intermediate inclined section 20 and lower section 21, thereby providing a channel for the passage of the tacks which is deeper at the top than at the bottom. The outer edge of the flange 19 is preferably beveled or curved, as shown at 55 19^a to permit free passage of the heads of the tacks, into the lower shallow portion of the channel which begins at the flange 19. The upper end 23 of plate 17 terminates some distance beneath the shoulders at the

upper ends of the halves 2 and 3 of the 65 hammer head, whereby tacks may pass from the chamber or magazine in front of the plate into the channel 15^a for delivery to the cut-off. Plate 17 is provided with a forwardly projecting lateral flange 24^a, which 70 divides the hollow hammer head in front of the channel 15^a into two chambers, a tack receptacle or magazine 24 communicating with the channel through the passageway 25 between end 23 of the plate and the shoulders 7, and a lower chamber 26 which receives a spring-pressed member for retaining a tack in setting position on the head, until the tack is released in the manner which will appear hereinafter. The tack 80 magazine 24 is closed by a swinging plate or cover 27 pivoted at 28 to the head and adapted when in closed position to rest on the front edges 29 of the hollow head. Preferably, the free end of cover 27 is bent, 85 as shown, and said bent end is adapted to enter a groove 30 formed in the top face of the head to retain the cover 27 in closed position. Mounted in a socket adjacent the top face of the head is a pin 31 having a 90 head 32 on the rear end of its shank. The shank of the pin projects through the socket in the head and the forward end of said shank is adapted to engage the cover 27. By pressing on the head 32 of the pin the 95 bent end of the cover may be sprung out of the groove 30, thereby releasing the cover and permitting it to swing into open position. In this way, access may be had to the magazine when it is desired to replenish 100 the supply of tacks.

Pivotaly mounted at 33 within the lower chamber 26 is a tack-retaining member or stop 34 having its lower face 35 curved to conform with the curvature of the flanges 105 15 of the enlargements 8. Said curved face 35 in effect forms a continuation of the channel wall formed by the plate 17 and the outer edge of said curved face is normally pressed toward or into engagement with 110 the flanges 15 to prevent exit of a tack out of the front face of the head, until effected by a rearward sliding movement or pull of the hammer head. The front face of the stop 34 normally lies flush with the front 115 edges of the head and beneath said front face the stop 34 is cut away, as shown at 36, to receive the free end of a leaf spring 37. This spring 37 passes beneath the pivot 28 of cover 27, and the free end of the spring 120 presses outwardly against the shoulder 36 of the stop to retain the latter normally in position to bar the exit of a tack.

The invention provides a novel cut-off operable to permit one tack at a time to pass 125 from the lower portion of the channel 15^a around into a dependent position from the striking face of the head, while the next

succeeding tack and all the other tacks in the channel are positively held against passage into such dependent position, until another operation of the cut-off is effected.

5 Pivotedly secured to an extension 5 and handle of the hammer by clips 38, 39, is a rod 40 having an arm 41, overlying the left hand lower flange 13 of the head and provided with a finger 42 adapted normally to extend across the slot 15^a of the channel and by engagement with the shank of the lowermost tack in said channel to bar further passage of the tacks through the channel. Finger 42 of the arm 41 is provided with a curved free end 43, as shown.

Coöoperating with the arm 41 is a second arm 44 adapted to retain all the other tacks against movement into setting position, when the arm 41 is operated to release 20 the lowermost tack in the channel 15^a, permitting the latter to pass around into setting position. As shown in Figs. 3 and 4, arm 44 is pivoted at 45 to the right hand extension 5 of the hammer head and overlies the lower right hand flange 13. Said arm 44 curves inwardly slightly, as indicated at 45, and is provided with a finger 46 adapted to engage finger 42 of arm 41. Finger 46 is also provided with a down- 25 wardly curved free end 47, into which normally fits the similarly shaped free end 43 of the arm 41. A spring 48 is secured at some convenient point, such as the inner end of the handle 4, and the free end of said 30 arm bears on the arm 44 so as to shift the latter toward the left and throw the curved portion 45 across the slot 15^a, when arm 41 is moved sidewise in the same direction. Normally, arm 44 is retained in 35 the position illustrated in Fig. 3, by the engagement of arm 41. The lower ends of arms 41 and 44 preferably work underneath upstanding guide plate 8^a, which prevent 40 displacement of said arms.

45 The operating rod 40 extends along the handle 4 and the end of the rod is provided with a finger 49 bent at an angle to the axis of the rod and adapted to be engaged by a projection 50 on the shank 51 of a finger piece 52. The shank of said finger piece is mounted in a recess in the handle 4 and is pivoted for oscillation on an axis 53 disposed at right angles to the axis of rotation of the rod 40. A spring 54 bearing against the rear face of the shank 51 maintains the finger piece and shank normally in forward position. When said finger piece 52 is pulled toward the rear, the movement imparted to projection 50 will 55 depress the finger 49 at the end of rod 40, and by a slight rotation of the operating rod, throw arm 41 toward the left, as indicated in Fig. 4.

Pivoted to the end 6 of the handle is a 60 gate 54 adapted to enter the slot 16 of the channel. When the hammer is in its proper position with the striking face 9 of the head beneath the handle, the gate 54 moves by gravity out of the slot permitting free passage of the tacks down the channel to the 65 cut-off. Reversal of the head, however, will cause the gate 54 to enter the slot 16 and prevent all the tacks which have previously moved into the lower portion of the channel from returning into the upper portion of 70 the channel.

The operation of the improved magazine hammer is as follows: The magazine 24 is supplied with tacks by opening the swinging cover or plate 27, and after the desired 75 quantity has been placed promiscuously in the magazine, the cover 27 is closed. By giving the hammer a few swings a number of the tacks may be shaken out of the magazine into the upper portion of the channel 80 85 15. As the tacks descend in the channel, the centrifugal force thoroughly shakes them up, and as the head of each tack comes into engagement with the curved edge 19^a, it is guided down the intermediate inclined portion of the channel into the lower portion. As shown, the heads of the tacks, which are arranged one above the other in the channel, are retained by the flanges 10 and the shanks project rearwardly through 90 95 the slot 16. The shank of the lowermost tack T' rests on the finger 42 of the arm 41 of the cut-off and the next succeeding tack T² is positioned in the channel just above tack T'. By pulling finger piece 52 rearwardly, rod 50 is imparted a slight oscillatory movement thereby shifting arm 41 to the left and moving finger 42 away from slot 15^a, whereupon tack T' drops beneath and passes around into a dependent position 100 from the striking face of the hammer, the head of the tack being retained by the flanges 15. The above set forth movement of arm 41 is accompanied by a movement in the same direction of the spring-impelled 105 arm 44, which movement of arm 44 throws the latter into engagement with the next succeeding tack T² and prevents the latter from dropping into dependent setting position. Release of the finger piece 52, permits arm 41 to return to its normal position, as illustrated in Fig. 3, thereby moving back the spring-impelled arm 44, so that the tack T² will drop into engagement with 110 115 finger 42 of arm 41, for release upon the next 120 operation of arm 41, in the same manner as has just been described.

Assuming that a tack is held in dependent position on the head, as shown, a blow from the hammer will set the tack in the article 125 to be tacked. As the tack is held by the article into which it has been set, a rearward sliding movement of the hammer head will

permit the head of the tack to force back the spring-impelled stop and free the tack from the hammer. The head of the tack passes out the front face of the hammer head.

5. What is claimed is:—

1. In a hammer, the combination of a hammer head, a tack magazine in said head, a substantially vertical channel in the head communicating with said magazine for delivering tacks into position to be set by a blow of the hammer, and a cut-off for controlling the delivery of tacks embodying a member positioned normally across the channel to block passage of the tacks, means for shifting said member to permit passage of the lowermost tack, and a spring-impelled member, movable into retaining engagement with the next succeeding tack on shifting of said first-named member.
- 10 2. In a hammer, the combination of a hammer head, a tack magazine in said head, a substantially vertical channel in the head communicating with said magazine for delivering tacks into position to be set by a blow of the hammer, and a cut-off for controlling the delivery of tacks embodying an arm having a finger positioned normally across the channel to block passage of the tacks, means for shifting said arm to permit passage of the lowermost tack, and a spring-impelled arm movable into retaining engagement with the next succeeding tack on shifting of said first-named arm.
- 15 3. In a hammer, the combination of a tack magazine, a channel communicating with said magazine for delivering tacks into position to be set by a blow of the hammer, and a cut-off for controlling the delivery of tacks embodying a pivoted arm having an operating rod extending along the hammer handle and a finger positioned normally across the channel to block passage of the tacks, means for oscillating said rod to swing said arm and permit passage of the lowermost tack, and a spring-impelled arm movable into retaining engagement with the next succeeding tack on swinging of said first-named arm into tack releasing position.
- 20 4. In a hammer, the combination of a tack magazine, a channel communicating with said magazine for delivering tacks into position to be set by a blow of the hammer, and a cut-off for controlling the delivery of tacks embodying a pivoted arm provided with a finger positioned normally across the channel to block passage of the tacks and having an operating rod extending along the hammer handle, a bent finger on the end of said operating rod, a spring-returned finger piece pivoted to the handle and engageable with the bent finger of the operating rod, said finger piece adapted when moved on its pivot to oscillate said rod and swing the arm in a direction to permit passage of the lowermost tack, and a spring-

impelled arm movable into retaining engagement with the next succeeding tack on swinging of said first named arm into tack releasing position.

5. In a hammer, the combination of a hammer head, a tack magazine in said head, a substantially vertical channel in the head communicating with said magazine through which tacks are delivered by gravity into position to be set by a blow of the hammer, and a cut-off for controlling the delivery of tacks embodying a member positioned normally across the channel to block passage of the tacks, means for shifting said member to permit passage of the lowermost tack, and a spring-impelled member movable into retaining engagement with the next succeeding tack on shifting of said first named member.

6. In a hammer, the combination of a hammer head, a tack magazine in said head, a substantially vertical channel in the head communicating with said magazine through which tacks are delivered into position to be set by a blow of the hammer, a cut-off for controlling the delivery of tacks embodying a member positioned normally across the channel to block passage of the tacks, means for shifting said member to permit passage of the lowermost tack, and a spring-impelled member movable into retaining engagement with the next succeeding tack on such shifting of said first named member, and a releasable stop for retaining a tack in setting position.

7. In a hammer, the combination of a hammer head, a tack magazine in said head, a substantially vertical channel in the head communicating with said magazine through which tacks are delivered into position to be set by a blow of the hammer, a cut-off for controlling the delivery of tacks embodying a member positioned normally across the channel to block passage of the tacks, means for shifting said member to permit passage of the lowermost tack, and a spring-impelled member movable into retaining engagement with the next succeeding tack on such shifting of said first named member, a stop adapted to retain a tack in setting position, and a spring for moving said stop into such tack retaining position.

8. In a hammer, the combination of a hammer head, a tack magazine in said head, a substantially vertical channel in the head communicating with said magazine through which tacks are delivered into position to be set by a blow of the hammer, a cut-off for controlling the delivery of tacks embodying a member positioned normally across the channel to block passage of the tacks, means for shifting said member to permit passage of the lowermost tack, and a spring-impelled member movable into retaining engagement with the next succeeding tack on such shifting of said first named member, a stop adapted to retain a tack in setting position, and a spring for moving said stop into such tack retaining position.

such shifting of said first named member, a stop engageable with the head of a tack in setting position to prevent release of the tack from the hammer, and a spring for moving

5 said stop into such tack retaining position.

9. In a hammer, the combination of a hammer head, a tack magazine in said head, a substantially vertical channel in the head communicating with said magazine through

10 which tacks are delivered into position to be set by a blow of the hammer, a cut-off operable to permit passage of the tacks one by one into setting position, and a releasable stop for retaining a tack in setting position.

15 10. In a hammer, the combination of a hammer head, a tack magazine in said head, a substantially vertical channel in the head communicating with said magazine through which tacks are delivered into position to be set by a blow of the hammer, a cut-off operable to permit passage of the tacks one by one into setting position, a stop adapted to retain a tack in setting position and a spring for moving said stop into such tack retaining

25 position.

11. In a hammer, the combination of a hammer head, a tack magazine in said head, a substantially vertical channel in the head communicating with said magazine through

30 which tacks are delivered into position to be set by a blow of the hammer, a cut-off operable to permit passage of the tacks one by one into setting position, a stop engageable with the head of a tack in setting position with the head of a tack in setting position to prevent release of the tack from the hammer, and a spring for moving said stop into such tack retaining position.

35 12. In a hammer, the combination with a head having a tack magazine therein, a channel in the head communicating with said magazine and receiving tacks shaken out of the magazine by the force produced in operating the hammer, said channel adapted to deliver the tacks into position to be set by a blow of the hammer, a cut-off operable to permit passage of the tacks one by one into setting position, and a releasable stop for retaining a tack in setting position.

deliver the tacks into position to be set by a blow of the hammer, and a cut-off operable 45 to permit passage of the tacks one by one into setting position.

13. In a hammer, the combination with a head having a tack magazine therein, a channel in the head communicating with said magazine and receiving tacks shaken out of the magazine by the force produced in operating the hammer, said channel adapted to deliver the tacks by gravity into position to be set by a blow of the hammer, and a cut-off 50 55 operable to permit passage of the tacks one by one into setting position.

14. In a hammer, the combination with a head having a tack magazine therein, a channel communicating with said magazine and receiving tacks shaken out of the magazine by the force produced in operating the hammer, said channel adapted to deliver the tacks into position to be set by a blow of the hammer, and a cut-off for controlling the delivery of tacks embodying a member positioned normally across the channel to block passage of the tacks, means for shifting said member to permit passage of the lowermost tack, and a spring-impelled member movable 60 65 into retaining engagement with the next succeeding tack on shifting of said first-named member.

15. In a hammer, the combination with a head having a tack magazine therein, a channel in the head communicating with said magazine and receiving tacks shaken out of the magazine by the force produced in operating the hammer, said channel adapted to deliver the tacks into position to be set by a blow of the hammer, a cut-off operable to permit passage of the tacks one by one into setting position, and a releasable stop for retaining a tack in setting position. 75 80

WILLIAM JACOBY.
